CHUTE SWITCHING MECHANISM

Sherman F. Corbell, Clifton, Ariz.

Application August 28, 1941, Serial No. 408,690

4 Claims. (Cl. 193—31)

This invention relates to a receiving receptacle for bottled goods or the like, and it is an object of the invention to provide a device of this kind including a receiving chute whereby it is possible to arrange the receptacle indoors to prevent pilfering of the goods delivered within the receptacle.

It is also an object of the invention to provide a receptacle of this kind having a plurality of compartments together with means operated by the articles delivered to the receptacle for causing the articles to be successively received within the compartments.

The invention consists in the details of construction and in the combination and arrangement of the several parts of my improved receiving receptacle whereby certain important advantages are attained, as will be hereinafter more fully set forth.

In order that my invention may be the better understood, I will now proceed to describe the same with reference to the accompanying drawings, wherein:

Figure 1 is a view in rear elevation of a receptacle constructed in accordance with an embodiment of my invention;

Figure 2 is a view in front elevation at the receiving end of the chute associated with the receptacle;

Figure 3 is a fragmentary view in top plan of the rear portion of the structure as illustrated in Figure 1;

Figure 4 is a vertical sectional view taken substantially on the line 4—4 of Figure 1, with the receptacle in working position; and

Figure 5 is a detailed sectional view taken substantially on the line 5—5 of Figure 1, with certain of the parts in different positions.

As disclosed in the accompanying drawings, W denotes the wall of a desired structure having provided therethrough the suitably positioned, downwardly and inwardly inclined slot 1 of desired dimensions. Snugly fitted within and extending through the slot or opening 1 is a tubular member M, the bottom wall 2 of which, at its outer end, is provided with a depending apron or flange 3 which has close contact with the outer face of the wall W and assures the proper maintenance of the member M in applied or working position. Disposed over the outer surface of the wall W is a plate 4 of desired dimensions and configuration and which is provided in its central portion with an opening 5 which registers with the outer open end of the member M. The top wall 6 of the member M, at its upper or outer

extremity, has hingedly connected therewith, as at 7, a swinging gate or flap 8 which is normally maintained by gravity in closed position, as particularly illustrated in Figure 4 of the drawings. It is to be noted that this flap or gate 8 is of such length as to have contact with the bottom wall 2 of the member M before reaching a vertical position.

The rear end of the member M is continued by a chute C, said chute at one side having its bottom wall 9 gradually increased in width, so that the lower end of the chute C is of a width materially greater than the width of the inner end of the chute, or that end of the chute immediately adjacent to and in communication with the member M. The side walls 11 of the chute C are in continuation of the side walls 12 of the member M. The outer or wider end of the bottom wall 9 of the chute C has depending therefrom a plate 14 of desired dimensions, and which plate constitutes the back wall for a receptacle R. The receptacle R is provided with the suitably spaced partitions 15 which, in connection with each other and with the side walls 16 of the receptacle R, provide a plurality of compartments 17, herein disclosed as three in number. Each of these compartments 17 is of such size and has its outer wall 18 so designed as to readily receive an individual article 19 of bottled goods or the like.

Each of the compartments 17 is open at its top and bottom and within the lower portion of each of the compartments is a rock arm 20, one end portion of which extends outwardly through a suitably positioned opening 21 in the back plate or wall 14 and is pivotally supported by a pivot rod 22 held in proper position by the outstanding lugs 23 carried by the back plate or wall 14. The rod 22 in the present embodiment of the invention is common to all of the arms 20. Carried by each of the arms 20 and positioned substantially centrally of the compartment 17 is a circular plate 24 of desired radius and suitably carried upon this plate 24 is a cushion pad 25 of a rubber compound or such other material as may be preferred.

The bottom wall 9 of the chute C, immediately adjacent to the back wall or plate 14, is provided with the upstanding partitions or walls 26, each of which is aligned with a partition 15. These partitions or walls 26 together with the side walls 11 of the chute provide runways, there being one runway for each of the compartments 17. At this time it is to be stated that the portions of the walls 11 immediately adjacent to the back wall or plate 14 are substantially parallel and

that the partitions or walls 26 are substantially coextensive in length with said parallel portions of the walls 11.

The outer ends of the partitions or walls 26 have hingedly connected therewith, as at 27, the switch arms 29, said arms when in open position having contact with the outwardly inclined portion of a wall 11, and for which reason one of said arms 29 is of greater length than the other. Each of these arms 29 is normally held at the limit of its outward or opening movement by a leaf spring 30. In the present embodiment of my invention one end portion of this spring 30 is suitably secured, as at 31, by welding or otherwise to a partition or wall 26, with the opposite or free end portion thereof having proper contact with its adjacent arm 29. Connected, as at 32, to the inner or hinged end portion of each of the arms 29 is an extremity of a flexible member 33. This member 33 extends out through a suitably positioned opening 34 in that portion of the bottom wall 9 of the chute C comprised in the runway 27 which is closed off by the switch arm 29 when in its open position. This flexible member 33 is of a length to extend through a suitably positioned opening 35 in the back wall or plate 14 so that said flexible member 33 can be secured to the rock arm 20 in the compartment 17 which is closed off by the arm. As before stated, the switch arms 29 are normally in an outward or closed position and, as herein disclosed, this leaves free for access a side or end compartment 17. An article, such as a bottle of milk or the like, inserted within the member M will ride down over the chute C into this end or side compartment 17. As this article 19 drops upon the pad 25 within such compartment the rock arm 20 will be depressed and for a distance sufficient to impose pull upon the connected flexible member 33 to throw the coating switch arm 29 into its closed position with respect to said side or end compartment, and in such position that when the next article is inserted within the member M it will be received within the next compartment 17, wherein the operation just recited will be repeated in connection with the second switch arm, except that this second switch arm when swung into its closed position will have contact with the previously closed switch arm 29. It is believed to be obvious that when the third article is placed within the member M it will be delivered within the next successive compartment.

Overlying the inner face of the wall W and in close contact therewith is a plate 36 of desired dimensions and configuration and, as illustrated in Figure 4, the lower portion of the applied member M passes through the lower portion of this plate 36.

Slidably disposed through the wall W and through the upper portions of both of the plates 4 and 36 are the rods 37. The outer end portion of each of these rods 37 carries a suitable indication 38 so that when the outer end of a rod 37 is projected the party delivering the articles will readily know the number desired. The rear ends of these rods 37 are provided with similar indications 39 and the outer faces of the plates 4 and 36 have placed thereon, closely adjacent to the rods 37, similar indications 40.

As illustrated in Figure 1, the lower end of this last-named compartment 17 is closed, as at 41, and resting upon this bottom 41 is a cushion pad 42 upon which the article drops.

From the foregoing description it is thought

to be obvious that a receiving receptacle constructed in accordance with my invention is particularly well adapted for use by reason of the convenience and facility with which it may be assembled and operated.

I claim:

1. A device of the class described comprising a receptacle divided into a plurality of article receiving compartments, a chute delivering to said compartments, said chute immediately adjacent to the compartments being divided into runways, there being one runway for each compartment, a pivoted switch arm at the entrance end of each of the runways for controlling said entrance end, each of said switch arms being movable independently of the remainder, means for normally maintaining each of said switch arms in an open position with respect to its associated runway and to close entrance to the adjacent runway, and means operated by the weight of an article received in one compartment for moving the switch arm associated with the runway delivering to said compartment to a position to close the delivery to said compartment and to guide a succeeding article to the adjacent compartment.

2. A device of the class described comprising a receptacle divided into a plurality of article receiving compartments, a chute delivering to said compartments, said chute immediately adjacent to the compartments being divided into runways, there being one runway for each compartment, a pivoted switch arm at the entrance end of each of the runways for controlling said entrance end, each of said switch arms being movable independently of the remainder, means for normally maintaining each of said switch arms in an open position with respect to its associated runway and to close entrance to the adjacent runway, and means operated by the weight of an article received in one compartment for moving the switch arm associated with the runway delivering to said compartment to a position to close the delivery to said compartment and to guide a succeeding article to the adjacent compartment, the compartments being vertically disposed and open at their upper ends, the chute being at the upper ends of the compartments and inclined downwardly toward said open ends.

3. A device of the class described comprising a receptacle divided into a plurality of article receiving compartments, a chute delivering to said compartments, said chute immediately adjacent to the compartments being divided into runways, there being one runway for each compartment, a pivoted switch arm at the entrance end of each of the runways for controlling said entrance end, means for normally maintaining each of said switch arms in an open position with respect to its associated runway and to close entrance to the adjacent runway, means operated by the weight of an article received in one compartment for moving the switch arm associated with the runway delivering to said compartment to a position to close the delivery to said compartment and to guide a succeeding article to the adjacent compartment, the means for moving a switch arm comprising a member within a compartment supported for movement lengthwise thereof, and a flexible member connecting the movable member and the switch arm, said movable member under the weight of the article thereon moving a distance sufficient to pull the flexible member to swing the switch arm into its second position.

4. A device of the class described comprising a receptacle divided into a plurality of article receiving compartments, a chute delivering to said compartments, said chute immediately adjacent to the compartments being divided into runways, there being one runway for each compartment, a pivoted switch arm at the entrance end of each of the runways for controlling said entrance end, each of said switch arms being movable independently of the remainder, means for normally maintaining each of said switch arms in an open position with respect to its associated runway and to close entrance to the

adjacent runway, and means operated by the weight of an article received in one compartment for moving the switch arm associated with the runway delivering to said compartment to a position to close the delivery to said compartment and to guide a succeeding article to the adjacent compartment, the portion of the chute adjacent the receptacle being gradually increased in width, the receptacle extending from substantially one side of the wider portion of the chute to the other side.

SHERMAN F. CORBELL.
